UNITED STATES PATENT OFFICE.

MARTIN P. ZIMMERMAN, OF CANTON, OHIO.

PUMP.

SPECIFICATION forming part of Letters Patent No. 248,381, dated October 18, 1881.

Application filed May 6, 1881. (No model.)

To all whom it may concern:

Be it known that I, MARTIN P. ZIMMERMAN, a citizen of the United States, residing at Canton, in the county of Stark and State 5 of Ohio, have invented certain new and useful Improvements in Pumps; and I do hereby declare the following to be a full, clear, and exact description of the invention, such as will enable others skilled in the art to which it appertains 10 to make and use the same, reference being had to the accompanying drawings, and to letters or figures of reference marked thereon, which form a part of this specification.

Figure 1 is a vertical section of a pump embodying my improvements. Fig. 2 shows the construction of the crank-shaft, and Fig. 3 shows another style of shaft.

In the drawings, A represents the body of the pump. It is formed with a single continuous chamber, B, extending from the top to the bottom.

C represents the lower part of the pump, and it may be made in one or more sections, as depth or other circumstances may require. 25 Between the body and the part C are placed a working-barrel, D, and a two-way-valve part, E. The working-barrel is formed separately from the body A and from the other parts, and is provided with two cylindrical pumping-tubes, d d, each carrying a piston. The upper end of the barrel is provided with a recess at c, wherein the upper part, A, is seated, and by means of which a tight joint between the barrel and the body is attainable. The two-way 30 part E is at the lower end attached to the section C by means of a central lower tube, E'. There are two separate tubes, e e, at the upper end of this part communicating with the central lower tube, E'. The separate tubes e e coincide with the tubes d d of the barrel D, and when the parts are joined together the lower tubes are fitted tightly within the upper ones. 35

m m are the valves, mounted on the top of the tubes e e, respectively. 40

By making the barrel separate from the body A and from the lower parts the operative parts of the pump can be cleaned and repaired much more readily than when the barrel or barrels

are formed within, or integral with, the body; and by making the pump body in the manner 50 shown, with one continuous chamber, and without the partitions heretofore used, I succeed in producing a more copious and steady flow than is obtained by the pumps constructed as heretofore.

The piston-rods O O are at their upper ends connected to the cranks p p on crank-shaft P. These cranks are not situated at some distance apart, in the usual manner, but are both placed as near as possible to the center of the pump. 60 To allow for such a connection the crank-shaft is bent to have a long transverse arm, o, at right angles to the shaft, and the cranks p p are arranged adjacent to this arm. When thus arranged in a pump having a cylindrical bore 65 the cranks can be made with a much longer radius than when parallel bars or arms q q at some distance apart are used, as shown in Fig. 3. Moreover, this arrangement requires fewer bends in the crank shaft, and thus avoids the 70 weakening incident to such bending. The rods O O are situated entirely within the body A, and I thus avoid the expensive features rendered necessary in those pumps having the delivery tube situated between the piston-rods. 75

By casting the seat or recess c on the barrel part D, I obviate the necessity of using bolts for fastening the parts together, said recess providing a sufficiently tight joint.

What I claim is— 80
The combination of the following elements, namely: the pump-body A, having the single central continuous chamber, B, the piston-rods O O, situated entirely within said central chamber, B, the pumping part D, formed separate 85 from the other parts, with the recess at c, and with two parallel barrels, d d, the tube-section C, and the intermediate part, E, having the diverging tubes e e joined to the barrels d d by fitting into their lower ends, as set forth. 90

In testimony whereof I affix my signature in presence of two witnesses.

MARTIN P. ZIMMERMAN.
